(57) **CLAIM**

The ornamental design for a lighting fixture element, as shown and described.

DESCRIPTION

FIG. 1 is a front view of the lighting fixture element, and the rear view thereof is a mirror image of FIG. 1;

FIG. 2 is a bottom view of the lighting fixture element;

FIG. 3 is a top view of the lighting fixture element;

FIG. 4 is a right side view of the lighting fixture element; and,

FIG. 5 is a left side view of the lighting fixture element.

The broken lines showing the how the lighting fixture element attaches to a rod are for illustrative purposes only and form no part of the claimed design. The stippling is for shading purposes only, and forms no part of the claimed invention.
